UNITED STATES PATENT OFFICE.

NILS D. LEVIN, OF COLUMBUS, OHIO, ASSIGNOR TO THE JEFFREY MANUFACTURING COMPANY, A CORPORATION OF OHIO.

ELECTRIC LOCOMOTIVE.

1,247,410.

Specification of Letters Patent.

Patented Nov. 20, 1917.

Application filed October 4, 1909, Serial No. 520,881. Renewed June 16, 1917. Serial No. 175,213.

To all whom it may concern:

Be it known that I, NILS D. LEVIN, a citizen of the United States, residing at Columbus, in the county of Franklin and State of Ohio, have invented certain new and useful Improvements in Electric Locomotives, of which the following is a specification, reference being had therein to the accompanying drawing.

10 This invention relates to electric locomotives of the type provided with reels for winding and unwinding electric conductor cables. Locomotives of this class are now well known and are especially adapted for 15 use in coal and similar mines to enter side entries and rooms which are not provided with trolley wires or other permanent conductors. In operation the conductor cable is secured to a trolley wire or other conductor, and current is supplied through the 20 cable to cause the locomotive to advance into a side entry or room. As the locomotive moves forward, the cable is automatically unwound from the reel. When the locomotive 25 returns, current is still supplied through the cable and the cable is automatically rewound upon the reel.

One of the objects of this invention is to 30 provide in a locomotive of the class described, an improved mounting of the motor and brake mechanisms for controlling the locomotive and of the reel and reel driving mechanism. A further object is to provide improved means for driving and controlling 35 the reel.

In the accompanying drawings, which 40 form a part of this specification, I have shown the embodiment of my invention which I consider preferable, but it will be understood that modifications and changes 45 may be made without departing from the spirit of my invention.

Of the drawings—

Figure 1 of the drawings is a side elevation of a locomotive equipped in accordance with my invention.

Fig. 2 is a plan view of same.

Fig. 3 is a side view of the reel and adjacent parts of the locomotive, to illustrate 50 the manner in which the reel is driven.

Fig. 4 is a vertical cross section of the reel.

1 indicates the main frame of the locomotive, which consists of a single casting 55 formed with the side-walls 2, 2, and the top

wall 3. In the four upper corners of this casting, cavities 4 are provided to serve as sand boxes.

Each of the side walls is recessed horizontally below and between these sand boxes, 60 and in the recesses are mounted the locomotive wheels 5, 5', fixed upon the axles 6, 6'.

Each of the side walls, 2, of the frame is formed with upwardly extending recesses 7 and 8 to receive axle boxes 9 and 10 and 65 axles 6, 6'. The forward recess 7 is smaller than the recess 8, and in it is secured in rigid position the axle box 10, between which and the side frame is suitably journaled the axle 6. It is evident that the forward axle 70 is not free to have vertical play with respect to the locomotive frame.

The rear axle, however, is journaled in vertically movable axle boxes 9 which slide in ways formed on the side walls of the recess 8. The usual springs 11 are interposed between the frame 2 and the axle boxes 9 to absorb shocks and jars. It will be observed that the more or less delicately constructed and adjusted reel mechanism, indicated as a whole, by the numeral 31, is mounted at the rear end of the locomotive 75 where it is protected from vibration by the springs 11; and that this spring-mounted end of the locomotive is also equipped with 80 the controlling levers and motorman's seat, so that the operator may be likewise protected from the jars to which the wheels 85 and axles are subjected.

The field frame parts 13 of the locomotive 90 motor are cast integrally with the locomotive frame 1. The armature shaft 14 of the motor is journaled in the centrally recessed parts 2' of the side plates 2 of the frame casting. The armature pinion 15 at one end 95 of the shaft meshes with the intermediate spur gear 16 on the stud shaft 16', which, in turn, meshes with the spur gear 17 on the shaft 17'. Mounted upon the same shaft with the spur gear 17 and rigidly connected 100 thereto is the pinion 18, which meshes with the gear wheel 19 mounted upon the forward locomotive axle. By means of this gearing, which is mounted so as to be bodily immovable with respect to the locomotive frame, 105, the power of the motor is transmitted to the forward axle 6' and the locomotive is propelled along the track. Since this axle is not movable bodily with respect to the locomotive frame, this gearing is at all times 110

properly in mesh and adapted to transmit power. The motor, however, is not subjected to the full strength of the shocks and jars which are received by the locomotive wheels, 5 the rear spring mounted axle boxes providing an elastic support for the motor parts and permitting the motor and the locomotive frame as a whole to yieldingly vibrate through small arcs about the forward axle 10 6 as a center.

The locomotive brake is applied to the motor armature 14 instead of to the car wheels, as is usually the case. Upon the outer end 15 of the armature shaft 14, the brake wheel 20 is keyed. The brake band 21, which frictionally engages the brake wheel in the usual manner is operated by means of the bell crank 22, connecting rod 23, bell crank 24, rod 25 and hand lever 26, the latter being mounted in a position handy to the motorman. By means of the lever 26 the brake 20 band can be tightened, and the armature shaft, the power transmitting gearing and the forward track wheels 5 can be retarded 25 and stopped.

At the rear end of the locomotive the motorman's compartment formed of structural steel is secured to the locomotive frame 1. It comprises side plates 27 and floor 30 plate 28. To this structural steel is secured the end frame 29. A similar end frame 30 at the front end of the locomotive is secured to the main frame casting 1. The cable reel 31 is rotatably mounted at the rear end of 35 the locomotive in bearing blocks 32 suitably supported upon the frame structure of the locomotive. It comprises the drum 33 made up of a plurality of circular wooden disks bolted together and the annular flanges 34 secured to the drum and adapted to prevent lateral displacement of the cable from the drum. The duplex cable 35 is forked at its inner end, one branch 36 being secured to the metallic hub piece 37 and the other 40 branch 38 leading to the hub 39. The cable 45 is passed through suitable antifriction guides 40 as it leaves the reel.

The two end shafts 41, 42 are rigidly seated in the wooden drum with their axes 50 in alinement. The inner adjacent ends of these stub shafts are separated by the insulating material of the drum and by means of the hubs 37, 39, by which they are surrounded. They are connected to the positive and negative conductors respectively of 55 the cable 35. The bearing box 32 is mounted on the wooden block 43, by means of which it is insulated from the locomotive frame. The current is conducted to the motor terminal by the wire 44, which is mechanically and electrically connected with the bearing 32 in the manner shown in Fig. 4 of the drawings. The other bearing 32 is 60 formed integrally with the iron standard 45, which is bolted to the floor plate 28 of

the motorman's compartment and serves to connect the return conductor 38 with the grounded terminal of the locomotive motor.

Rope wheel 46 is formed as an integral part of the same casting with the hub 39 and 70 is engaged by the drive rope 47, which also passes around the rope pulley 48, which is rigidly secured to the axle 6'. The tension in the drive rope is regulated by the idler pulley 49, which is journaled in one end of 75 the foot lever 50. This lever is pivoted intermediate of its ends at 51 to standard 45 and at its other end is provided with a foot rest 52, by means of which the motorman can increase or diminish the tension in the 80 rope 47. Stub shaft 41 has keyed upon it the hand wheel 53 which serves as additional means for controlling the unwinding of the reel and as a means for manually rotating the reel in a winding direction. The motorman may prevent the over-running of the cable when the locomotive is moving away from the fixed conductor by holding his hand against the hand wheel 53. When the locomotive is slowing down and the cable is 85 paying out too freely, the rotation of the reel can be checked by tightening the rope 47, which then acts as a brake. At times when the locomotive is coming out of a room and the cable is being wound upon the reel, 90 the treadle lever 50 is used to apply pressure between the rope wheels sufficient to cause the reel to wind the cable without, however, being great enough to bring about an undue strain in the cable.

Because the brake is applied to the locomotive motor, which is geared to but one of the pairs of driving wheels and because the other pair of driving wheels are connected to the reel, the locomotive can be freely and rapidly stopped, even so quickly as to skid the front wheels 5, without affecting the uniform and steady transmission of power from the rear pair of wheels to the reel. In this way, the winding of the cable is provided 100 for at all times when the locomotive is moving toward the outer end of the cable, and the formation of slack in the cable in front of the locomotive and the cutting of this slack cable by the track wheels is entirely 110 prevented.

What I claim is—

1. In an electric locomotive, the combination of a frame, two axles, on one of which the frame is unyieldingly and on the other 120 yieldably mounted, track wheels for the axles, an electric motor on the frame geared to the first said axle, a cable-reel mounted on the frame, flexible driving devices connecting the reel and the second said axle, and a 125 conductor cable on the reel adapted to carry current from a fixed conductor to the said motor.

2. In an electric locomotive, the combination of a frame, two axles, on one of which 130

the frame is unyieldably mounted and on the other of which the frame is yieldably mounted, track wheels for the axles, an electric motor rigidly mounted on the frame and 5 geared to the first said axle, a manually controllable brake connected for resisting the rotation of the first said axle, a cable reel on the frame adjacent the second said axle, flexible driving devices connecting the reel and 10 the second said axle, and a conductor cable on the reel adapted to carry current from a fixed conductor to the said motor.

3. The combination in an electric locomotive of a frame, a pair of axles, on one of 15 which the frame is unyieldably and on the other yieldably mounted, track wheels for the axles, driving mechanism for the rigidly mounted axle mounted in fixed position on the frame comprising a motor and power 20 transmitting mechanism between the motor and axle, a brake mechanism acting directly on the driving mechanism to retard the rotation of the rigidly mounted axle only, a

cable reel, a conductor cable wound thereon and electrically connected with the motor, 25 and power transmitting mechanism connecting the unbraked axle with the reel.

4. In an electric locomotive, the combination of a frame, two axles on one of which the frame is rigidly mounted and on the 30 other of which it is mounted vertically yieldably, track wheels for the axles, a motor rigidly mounted on the frame, gearing between the motor and the rigid axle, a cable reel on the frame, a conductor cable electrically connected to the motor and adapted 35 to be wound on the reel, and a power connection between the yieldable axle and the reel comprising a frictionally acting endless flexible power transmitting element. 40

In testimony whereof I affix my signature, in presence of two witnesses.
